UNITED STATES PATENT OFFICE.

CHARLES H. JOHNSON, OF BOYLSTON, AND GEORGE E. JOHNSON, OF WORCESTER,
MASSACHUSETTS.

SIGNAL SYSTEM.

1,163,346.

Specification of Letters Patent.

Patented Dec. 7, 1915.

Application filed April 6, 1915. Serial No. 19,548.

To all whom it may concern:

Be it known that we, CHARLES H. JOHNSON and GEORGE E. JOHNSON, citizens of the United States, residing, respectively, at 5 Boylston and Worcester, both in the county of Worcester and State of Massachusetts, have invented a new and useful Signal System, of which the following is a specification.

10 This invention relates to a call or annunciator system for use in sounding or displaying calls at one or a number of stations, giving fire or other emergency alarms, or conveying information of other kinds.

15 The principal objects of the invention are to provide a simplified mechanism for this purpose which involves only a single mechanism at a central station, and call bells, lights, annunciators, or the like at the stations where the signals are to be given; to provide a construction in which, with an exceedingly compact arrangement, a large number of different signals can be given; to provide a construction in which the chance 20 of inadvertently giving a prior signal over again or making a mistake in the signal to be given is substantially eliminated, by providing means whereby the signal-giving mechanism is always released and restored to normal condition upon the manipulation 25 of the device for the purpose of setting it for giving another signal; to provide an improved key board mechanism for this purpose; to provide an improved selector connected therewith and controlled thereby; to provide means, preferably constituting a 30 part of the selector itself, for preventing arcing at the different contact points and concentrating all the arcing at a single pair of contacts; and to provide an improved contact-making device for making or breaking the main circuit, this being controlled 35 by a controlling circuit.

40 The invention also involves improvements in details of construction of the various parts as will appear.

Reference is to be had to the accompanying drawings; in which;

45 Figure 1 is a front elevation of a controlling key board constructed in accordance with our invention, parts being shown in section on different planes back of the front thereof; Fig. 2 is a sectional view on the line 2—2 of Fig. 1; Fig. 3 is a front elevation of the selector ring showing its connec- 50

tions with the clock work in section on a plane parallel with the front of the selector ring; Fig. 4 is a diametrical sectional view of the selector ring on the line 4—4 of Fig. 3; Fig. 5 is a side elevation of the main contact-making device showing the insulating plate supporting the key board in section; and Fig. 6 is a diagrammatic view showing the electrical connections. 60

The invention is shown in a form comprising a key board A, and a selector B, adapted to be controlled by the key board and itself controlling connections in a controlling circuit a a', so that a contact-making device C will operate simultaneously with it, thus 65 controlling an external high-tension circuit c which operates the signal or alarm devices, shown in this case as bells E and lamps D. A double-pole switch F is shown for connecting and disconnecting the external circuit. When this switch is closed so that the device is ready to operate, a red lamp G is 70 lighted, and whenever the contact is made at C, a white light H is lighted. The external circuit is shown as in the form of a three-wire circuit and need not be described in detail. 75

The key board is shown as mounted on an insulating plate 10 and comprises a metallic frame-work 11 supporting a front plate 12 and the other elements of the key board. This front plate is provided with two series of push buttons 1^a, 2^a, 3^a, 4^a, 5^a, 6^a, 7^a, 8^a and 1^b, 2^b, 3^b, 4^b, 5^b, 6^b, 7^b, 8^b, 9^b. It will be understood, of course, that although we have shown two series of these push buttons, the invention is not limited to any particular number of series. Both series of push buttons are alike, and the one shown in Fig. 2 will be described. In this case each push button is provided with a shank 14 on which the button itself is mounted and which is adapted to move transversely to the front plate 12 upon the pressing of the button. On the end of this shank is a fiber or other insulating tip 15. These tips rest on movable contact members, in the form of springs 16. Each of these springs is fixed to a cross-bar 17 and is insulated therefrom by a fiber disk or the like 18, and each spring at the point at which it is fixed to this bar is provided with a fastening bolt having a head 19 constituting a stationary contact permanently connected with the spring by the bolt, but insulated from 90

100

105

110

the cross bar 17. It will be noticed that these springs are so arranged that each one normally contacts with the bolt head of the next spring below and that when one of the 5 push buttons is pushed down, that spring is pressed away from its contacting bolt head. These springs serve a double purpose, as they hold the push buttons out to the front and restore them to that position when allowed to do so, and they also make electrical contacts in series, as will be observed from Figs. 2 and 6. These bolts and their springs at the left are provided with a series of wires 1^a, 2^a, etc. These wires constitute branch circuits, each one of which is connected with a terminal 1^a, 2^a, etc., of the selector B.

Although we have described only one set 20 of connections, it will be understood that in the other column corresponding connections are present.

The push buttons 1^b, 2^b, etc., are connected by branch wires 1^b, 2^b, etc., to terminals 1^b, 2^b, etc., on the selector. Fig. 2 shows this second column, and in this case there is an additional feature, namely, a conducting bar 21 having a series of springs 22 thereon normally out of contact with the springs 16, but when one of the push buttons of this series 30 is depressed, the springs on which it rests will not only break its contact with the bolt head 19, but it makes contact with one of the springs 22 at substantially the same time. The purpose of this will be described in connection with the wiring diagram.

It is to be noted that each of the shanks 14 is provided with a conical member 23. Furthermore, there are reciprocable detent plates 24, one for each series of push buttons, and each having perforations therethrough for receiving these conical members. In the form shown in the drawings, the key board is in upright position and consequently these detent plates are capable 45 of dropping by gravity, being guided by the end posts of the frame-work 11. Under normal conditions, they are free to drop, and when any one of the push buttons is pushed in, as for example the button 4^b in Fig. 2, as 50 soon as the shoulder on the conical member passes beyond the rear surface of the plate 24, the latter is free to drop and pass over the shoulder, thus positively holding that push button in its depressed position; but 55 if at any time another button is pressed, it releases the one held depressed because it pushes back the detent plate and then allows it to drop again, but only after the first push button has sprung back. From this it 60 will be seen that there is no danger of any confusion or of setting two buttons of the same series at the same time, and that if the operator forgets to release the previously pressed push buttons, or if for any 65 reason the mechanism does not release them,

the setting of the key board to give a different signal will automatically release them.

The selector B consists of a ring 25 of fiber or other insulating material, provided in the present case with two series of metallic contacts 1^a, 2^a and 1^b, 2^b, etc., projecting inwardly from the inner cylinder surface of the ring. The connections of these contacts with the push button springs have been described already. This small selector ring 75 is mounted in stationary position on the bottom of a clock work K and the central shaft 26 of the clock work projects through into the center of the selector ring. On this shaft is a disk 27 which rotates with it and on this disk is a pin or stud 28 carrying a pivoted arm 29. Fixedly mounted on the disk is a cleat or the like 30, having a spring 33^a for forcing the contact arm against the inner surface of the ring 25. Also mounted 85 on this cleat is a contact screw 31, and on the arm 29 is a contact pin 32 spring-pressed toward the contact screw 31. It will be seen, therefore, that as the disk 27 rotates, the end of the contact arm 29 is normally 90 in contact with the insulating inner surface of the selector ring and held there by the spring 33^a. When it engages one of the convex metallic contacts 1^a or the like, it rides up on the same but does not complete 95 an electrical circuit until forced inwardly far enough to make the contact 32 engage the screw 31; and before the end of the arm 29 leaves the convex surface of the contact pin 1^a or the like, the contact will be broken 100 at 31 and 32 and in this way all the arcing will take place at this contact, and it can be made of carbon or other non-oxidizing material for this purpose. The spring 33^a, of course, is insulated from one or both of the 105 members 29 and 30. In this case an insulating bushing 33 is shown for that purpose. The arm 29 is insulated from the stud 28 and disk 27 by an insulating bushing 34.

The clock work for operating the selector 110 has no special features, so far as the clock work itself is concerned, and will not be described in detail, but it is provided with a winding shaft 35 which is turned around 115 in order to wind up the clock. On this winding shaft is a cam 36 which, at the end of a rotation of the winding shaft, engages a spring-pressed lever 37 and presses a contact screw 38 thereon into engagement with a contact point 39 fixed on an insulating block 40 on the clock work. The connection of this with the rest of the apparatus will be described in connection with the diagram. Mounted on another shaft constituting a part of the clock work, is an arm 41 which, at the end of the revolution, is adapted to engage a spring-pressed stop pin 42 so as to bring the clock work to rest always in the same position.

Referring now more especially to the dia- 120

gram, Fig. 6, it will be seen that the controlling circuit a a' is connected with a battery 45, having two poles 46 and 46^a. The pole 46 is connected directly with two electro-magnets 47 and 48 in series by wire b in parallel with the wires a a' . The armatures 49 and 50 of these electro-magnets are connected with the detent plates 24 which have been described. Also, in series with these magnets is a wire connected with the contact spring 39. The metallic clock work frame is connected by a binding post 51 through the back of the plate 10 with a wire a' which is connected directly with the other pole 46^a of the battery. This latter wire, therefore, is directly connected with the central shaft 27 of the clock work and selector so that the latter can be connected by means of the arm 29 and the contact points on the interior of the selector with the push buttons on the key board. These push button contacts of the two series are connected in multiple with each other and both in series with the wire a which extends to an electro-magnet 53 and from there back to the battery pole 46. It may be mentioned here that this electro-magnet is provided with an armature 54 on a pivoted arm 55, which is provided with a pivoted carbon contact member 56 pressed by a spring 57 toward its other contact member 58 and thus capable of a sliding contact. A spring 59 normally keeps these contacts apart and a stop screw 60 limits the distance apart of the contact points. The object of this mechanism is to complete the outside circuit, as indicated on the diagram, and to provide a rubbing contact which will be capable of arcing without injuring the surfaces of the contact points, one of them being carbon and the other copper, preferably.

The operation of the device will now be described.

Assuming that it is desired to ring the number 34, the buttons 3^a and 4^b are depressed, both of the detent plates 24 then drop so as to hold these two buttons in depressed condition. The depression of the button 3^a depresses the corresponding spring 16 and breaks the contact of the third spring 16 with the fourth bolt head 19. Consequently, the circuit is broken at all points beyond the third push button. But the battery 45 is still in condition to be connected with the three contact points 1^a, 2^a and 3^a, the other contact points in that series being dead. Likewise, the depression of the button 4^b cuts out all the contact points 5^b, 6^b, etc., so that they cannot be connected with the apparatus while the button is down. The depression of this latter button also connects the springs 16 which are left in circuit with the plate 21, and thus brings the connection back to the battery.

Now if the clock is wound up by turning

the main shaft a revolution, the stop arm 41 is turned around to the dotted line position of Fig. 1 and then immediately commences to turn back with the main shaft. This main shaft is designed in the present case to make three revolutions before the stop arm comes into position to stop it. It starts from the normal position shown in Fig. 3 and as the arm 29 passes over points 9^a, 8^a, 7^a, 6^a, 5^a, 4^a, these points are dead, but it signals at point 3^a, 2^a and 1^a. Then there is a rest till it touches the contact 1^c. As it passes over a live contact point of the first series, as 3^a, it completes the circuit from the battery terminal 46^a, through the wire a' , clock work, terminals 31, 32, arm 29, contact 3^a, wire 3^c, spring 16, wire a , electro-magnet 53, back to the battery terminal 46. As previously described, however, it will be understood that it is not the mere contact of the arm 29 with the contact point 3^a that completes this circuit, but the contact of the two members 31 and 32 and this is where the arcing naturally takes place. The result of this contact is to energize the magnet 53 and thus close the outside circuit at the points 56 and 58. This gives signal 1 on the bells E, lights D, or whatever other signals are employed; it also lights the lamp H. Having sounded or given this alarm, the contact 56-58 is immediately broken by the deenergizing of the magnet 53 when the arm 29 passes far enough over the contact 3^a to separate the contacts 31 and 32, and the rotation continues so as to perform the same operation at the contacts 2^a and 3^a with a short interval between each two of them. As the arm 29 engages the first contact point 1^c of the other series on the selector, a circuit is created in a similar way from the terminal 46^a to the other terminal 46 of the battery. But in this case the current passes through the wire 1^c, one of the springs 22 and plate 21. The next three contacts at 2^c, 3^c, and 4^c give the same result, but those beyond being dead, that ends the signal for that revolution. It will be seen, therefore, that the signal 34 has been sounded or otherwise indicated. According to the gearing of the clock work, these signals may be repeated two, three or more times as may be desired, during one revolution of the main shaft. At the end of that revolution, after the last signal has been finished, the cam 36 comes into contact with the arm 37 and forces it over to connect the contacts 38 and 39. In this way a shunt is created from the terminals 46 through the wire b , electro-magnets 47 and 48, terminals 38 and 39, clock work casing, binding post 51, and wire a' , to the other terminal 46^a. This energizes the two magnets 47 and 48 which act to attract their armatures 49 and 50 to raise the two detent plates 24. This releases the push buttons that have been de-

130

pressed and then the cam 36 passes beyond the arm 37 and breaks the branch circuit *b* so that the magnets are each deenergized and the detent plates 24 restored to their normal condition in which they are free to drop and lock any push button that is depressed thereafter.

The full operation of the device having been described, attention should be called to the fact that it is not necessary to give a signal in two figures. If the signal 6, for example, is desired, the push button 6^a is depressed. The six signals will be given in the way that has been described, and when the selector arm 29 passes over the second series of the contacts 1^f, etc., they will all be dead, because there is no connection with the connecting bar 21 on the right-hand series of push buttons. It is to be noted that in order to ring a single number, the corresponding push button in the tens column of push buttons has to be depressed.

We are aware of the fact that if the clock work is started, with everything else in working condition, without any push buttons being depressed on the left-hand series, the signal 9 will be given, because no one of the branch circuits is cut out, and all the terminals on that side of the selector are alive or in condition to be connected up by the rotation of the selector arm. On this account it is desirable to have the signal 9 indicate a test or the like. Usually the push button 9^a will be depressed, however, for the purpose of giving that signal. However, this is not true of the right-hand push buttons, because the corresponding contact points are always dead unless one of them is depressed.

It will be seen from consideration of the description given and the drawings connected herewith, that by this extremely simple and compact arrangement, a calling system is provided which is not limited to a small number of calls, as is the case with the devices on the market. Without any material complications of the key board or of the selector, ninety different calls are provided by this mechanism, and by the simple addition of a third row of push buttons and the division of the selector into three series instead of two, thus increasing its diameter very little, nine hundred calls can be sounded; also the method of getting all the sparkling at one point is exceedingly simple and requires no mechanism outside the selector and increases the cost of the device very slightly indeed.

Although we have illustrated and described only a single embodiment of the invention and shown it as applied to a particular calling system, we are aware of the fact that many modifications can be made in the construction and arrangement of parts, and that the invention can be applied with-

out changing its essential features for practical use in calling systems of other kinds, automatic announcing systems, automatic fire alarms, and other emergency alarms and many other devices. Therefore, we do not wish to be limited to the details of construction herein shown and described, nor to the particular calling system with which we have shown it as being connected, but

What we do claim is:—

1. In a device of the character described, the combination of a plurality of stationary contacts, a plurality of movable contact members, each permanently in electrical connection with one of said stationary contacts and normally in contact with the next one, whereby said contacts are normally connected with each other in series, a plurality of wires one connected with each of said contacts, a main connected with the first of said movable contacts, and means for moving said movable contact members individually to disconnect them from the contacts which they normally engage.

2. In a device of the character described, the combination of a plurality of contacts, a plurality of movable contact members, each in electrical connection with one of said contacts and normally in contact with the next one, whereby said contacts are normally connected with each other in series, a plurality of wires one connected with each of said contacts, a main connected with the first of said movable contacts, and means for moving any one of said movable contact members out of contact with the next stationary contact whereby all those beyond it will be disconnected from said main.

3. In a device of the character described, the combination of a plurality of stationary contacts, a plurality of movable contact members, each permanently in electrical connection with one of said stationary contacts and normally in contact with the next one, whereby said contacts are normally connected with each other in series, a plurality of wires one connected with each of said contacts, a main connected with the first of said movable contacts, and means for moving said movable contact members individually to disconnect them from the contacts which they normally engage, and means whereby when any of said movable contact members is so disconnected, the disconnection of another one in the same series will restore the first named movable contact member to normal condition.

4. In a device of the class described, the combination of a plurality of push buttons, a plurality of movable contact members, one for each push button, a plurality of stationary contacts, said movable contact members normally engaging the stationary contacts, and being adapted to be moved out of engagement with them by the depre-

sion of the respective push buttons, a plurality of branch circuits, one connected with each of said contacts, whereby when a push button is depressed the contact member connected with it will be disconnected from its stationary contact and all the branch circuits in the series beyond will be disconnected from the circuit.

5. In a device of the class described, the combination of a series of push buttons, a series of springs, one for each push button, a series of contacts, said springs normally acting to hold the push buttons up and to engage said contacts, thereby connecting said contacts in series, a main connected with the first contact, and a plurality of branch circuits, one connected with each of said contacts, whereby when a push button is depressed the spring connected with it will be disconnected from its contact and all the branch circuits beyond it in the series will be disconnected from the main.

25 be disconnected from the main.

6. In a device of the class described, the combination of a series of push buttons, a series of springs, one for each push button, a series of contacts, said springs normally acting to hold the push buttons up and to engage said contacts, thereby connecting said contacts in series, a main connected with the first contact, a plurality of branch circuits, one connected with each of said contacts, whereby when a push button is depressed the spring connected with it will be disconnected from its contact and all the branch circuits beyond it in the series will be disconnected from the main, a second series of push buttons, springs and contacts like the first named series but having no direct connection with the main, and a conducting member connected with the main and having means whereby when any one of said springs of the second series is depressed by the depression of the corresponding push button, all the springs in that series before it will be electrically connected with said conducting member and main.

7. In a device of the class described, the combination of a series of push buttons, a series of springs, one for each push button, 50 a series of contacts, said springs normally acting to hold the push buttons in one position and to connect all of said contacts in series, a plurality of branch circuits, one connected with each of said contacts where- 55 by when a push button is depressed the spring connected with it will be disconnected from its contact and all of the branch circuits in the series beyond it will be disconnected from the circuit, a source of power 60 connected with the first one of said springs, a second series of push buttons, springs and contacts like the first named series but having no direct connection with the source of power, a conducting plate connected with 65 the source of power and having means

whereby when any one of said springs of the second series is depressed by the depression of the corresponding push button, all of the springs in that series before it will be electrically connected with said plate, two 70 detent plates, and means whereby each detent plate is adapted to hold any depressed button of one series in depressed position until said detent plate is moved.

8. In a device of the class described, the combination of a series of push buttons, a series of springs, one for each push button, a series of contacts, said springs normally acting to connect said contacts in series, a plurality of branch circuits, one connected with each of said contacts, whereby when a push button is depressed the spring connected with it will be disconnected from its contact and all of the branch circuits in the series beyond it will be disconnected from the circuit, and a source of power connected with the first one of said springs, said push buttons having shoulders thereon, a detent plate provided with perforations through which said shoulders are adapted to pass and arranged to normally press against one side of the shoulders, whereby it will lock any push button in depressed position until the plate is moved.

9. In a system of the class described, the combination of a key board having a plurality of keys, each adapted to be depressed, a plurality of springs normally connected with each other in series, a battery, one terminal of which is connected with the first spring, means for moving each spring to disconnect that spring from the next spring beyond it in the series when any key is depressed, a plurality of branch circuits, one connected with each of said springs, a selector having a series of contacts, one connected with each of the branch circuits, a contact arm, means for causing a relative movement between the contact arm and contacts, whereby said contacts will be connected in succession with the contact arm, and means for connecting said contact arm with the other terminal of the battery. 100 105 110

10. In a system of the class described, the combination of a plurality of springs normally connected with each other in series, a battery, one terminal of which is connected with the first spring, of means for moving each spring to disconnect that spring from the next spring beyond it in the series, a plurality of branch circuits, one connected with each of said springs, and a selector having a series of contacts, one connected with each of the branch circuits.

11. In a system of the class described, the combination of a key-board having a plurality of keys, each adapted to be depressed, a series of springs, each key having means for moving a spring so as to disconnect that spring from the springs beyond it in 130

the series when the key is depressed, a source of power, one terminal of which is connected with the first spring of the series, a plurality of branch circuits, one connected with each of said springs, a selector having a corresponding series of contacts, one connected with each of the branch circuits, a contact arm, means for causing a relative movement between the contact arm and selector, whereby said contacts will be connected in succession with the contact arm, a circuit for connecting said contact arm with the other pole of the source of power, an electro-magnet in said circuit, and an external circuit having a pair of contacts adapted to be operated by the action of said electro-magnet.

12. In a calling system or the like, the combination with a key-board, of a selector, a plurality of branch circuits, the selector having a series of terminals, each permanently connected with one of said branch circuits, means for connecting said terminals with a source of power periodically, said key-board being provided with a series of 25 spring contacts and keys, each spring contact being normally connected with one of said branch circuits and arranged to disconnect all the branch circuits beyond when any key is depressed.

13. In a device of the character described, the combination of a plurality of push buttons, a plurality of springs, one for each push button for holding the push buttons in normal position, a plurality of contact members adapted to be engaged in series by said springs when in normal position, whereby upon the depression of a push button, one of said springs will be disconnected from its contact member and all the contact members beyond it will be electrically disconnected from it, a source of power connected with the first spring, a clock-work, a selector having a series of contacts each connected with one of said springs and provided with an arm operated by said clock-work for passing over said contacts, said arm being connected with the other terminal of said source of power.

14. In a device of the character described, the combination of a plurality of push buttons, a plurality of springs, one for each push button for holding the push buttons in normal position, a plurality of contact members adapted to be engaged in series by said springs when in normal position, whereby upon the depression of a push button one of said springs will be disconnected from its contact member and all the contact members beyond it will be electrically disconnected from it, a source of power connected with the first spring, a clock-work, a selector having a series of contacts each connected with one of said springs and provided with an arm operated by said clock-work for passing over said contacts, said arm being con-

nected with the other terminal of said source of power, a detent plate for holding a push button in depressed position, an electro-magnet having means for removing said detent plate from its holding position when the electro-magnet is excited, said electro-magnet being connected with said source of power, and means connected with the clock-work for connecting the other pole of the electro-magnet with said source of power when the clock-work has run a predetermined length of time.

15. In a device of the character described, the combination of a series of push buttons, a plurality of springs, one for each push button for holding the push buttons in normal position, a plurality of contact members to be engaged in series by said springs when in normal position, whereby upon the depression of a push button one of said springs will be disconnected from its contact member and all the contact members beyond it will be thrown out of the circuit, a source of power connected with the first spring, a clock-work, a selector having a series of 90 contacts each connected with one of said springs and provided with an arm operated by said clock-work for passing over said contacts, said arm being connected with the other terminal of said source of power, said selector arm being provided with a contact point in series with said springs, and means whereby said contact point will be caused to complete the circuit after the arm has engaged one of the contacts of the selector, and to break it before the arm has been disengaged therefrom.

16. In a device of the character described, the combination of a clockwork, a series of contacts, branch circuits connected with said contacts, an arm operated by said clockwork for passing over said contacts, said arm being connected with the terminal of a source of power and being provided with a contact point, said branch circuits having means by which they are normally connected with the other terminal of said source of electricity, means whereby all of said branch circuits beyond any desired point in the series can be disconnected from the source of electricity, and means whereby said contact point will be caused to complete the circuit after the arm has engaged one of said series of contacts and to break it before the arm has been disengaged therefrom.

17. In a selector, the combination of a ring of insulating material, a series of conducting members having contacting surfaces on a surface of said ring, branch circuits connected with said conducting members, a shaft concentric with said ring connected with a source of electricity and having an arm thereon adapted to engage said contacting surfaces, said branch circuits hav-

- ing means by which they are normally connected with the other pole of said source of electricity, means whereby all of said branch circuits beyond any desired point in the series can be disconnected from the source of electricity, and means for causing a relative rotation between the shaft and ring.
18. In a selector, the combination with an insulating member having conducting contact points along one surface thereof insulated from each other by the material of the member, branch circuits connected with said contact points, a contacting arm, means for causing a relative motion between the arm and said insulating member, whereby the arm contacts with said contact points one after the other in succession, said arm being connected with a source of electricity, said branch circuits having means by which they are normally connected with the other pole of said source of electricity, and means whereby all of said branch circuits beyond any desired point in the series can be disconnected from the source of electricity.
19. In a selector, the combination of a ring of insulating material, a series of radial conducting members having contacting surfaces on the surface of said ring, a controlling circuit having branch circuits connected with said conducting members, a shaft concentric with said ring connected with a source of electricity and having an arm thereon adapted to engage said contacting surfaces, means for causing a relative rotation between the shaft and ring, an external circuit having alarm devices therein adapted to be energized when the circuit is closed, and means controlled by the first named circuit for completing the external circuit.

In testimony whereof we have signed our names to this specification in the presence of two subscribing witnesses.

CHARLES H. JOHNSON.
GEORGE E. JOHNSON.
